CLAIM

I claim the ornamental design for an upper receiver for a firearm or the like, as shown and described.

DESCRIPTION

FIG. 1 is a perspective view of an upper receiver for a firearm or the like showing the new design;
FIG. 2 is another perspective view thereof;
FIG. 3 is a left side elevation view thereof;
FIG. 4 is a right side elevation view thereof;
FIG. 5 is a top plan view thereof;
FIG. 6 is a bottom plan view thereof;
FIG. 7 is a rear elevation view thereof; and,
FIG. 8 is a front elevation view thereof.
The broken lines illustrate features of the upper receiver for a firearm or the like that form no part of the claimed design.
